TENNIS DART GAME BOARD

Wilfred R. Pobursky, 28514 Bock St., Garden City, Mich.

Filed Sept. 8, 1959, Ser. No. 57,453

Term of patent 14 years

(Cl. D34—5)

FIG. 2

Fig. 1 is a perspective view of a tennis dart game board showing my new design; and

Fig. 2 is an edge view thereof.

I claim:

The ornamental design for a tennis dart game board, substantially as shown.
